UNITED STATES PATENT OFFICE

BLUFORD W. BROCKETT, OF CLEVELAND HEIGHTS, OHIO, ASSIGNOR, BY DIRECT AND MESNE ASSIGNMENTS, OF ONE-HALF TO THE AMERICAN LAUNDRY MACHINERY COMPANY, OF NORWOOD, OHIO, A CORPORATION OF OHIO, AND ONE-HALF TO UNITED STATES HOFFMAN MACHINERY CORPORATION, OF NEW YORK, N. Y., A CORPORATION OF DELAWARE

PRESSING MACHINE

Application filed August 31, 1925. Serial No. 53,544.

This invention relates to platen type presses used in pressing garments either in the laundry or the garment pressing trade.

Heretofore presses for these fields have been substantially of one or the other of two types. One type is what might be termed the automatic press where the controller, when actuated, starts the mechanism driven by motor means for closing the press and applying final pressure and thereafter when again operated opens the press. The other type is one where the head is closed by hand upon the work and power is afterwards applied either automatically or by "will of the operator" control. By reason of the wide opening of the head and bed and the necessity to direct and hold some lays of the garment upon the bed, the first type of machine is extremely dangerous, clumsy and inefficient because in twenty-five per cent of the operations the operator's hands are upon the bed as the press closes and injury to the operator results or a poor pressing operation is produced, the latter requiring an additional pressing operation to cure the previous imperfect performance.

In order to protect the operator and improve the efficiency of the machine, of the first type, guards and safety devices have been provided but in all such arrangements the construction has been such that the operator cannot hold or conduct the difficult lays at the time of closing of the press with the result that the article falls away or becomes disturbed before the pressing operation, requiring further treatment. These presses are effective for a large proportion of the operations but the balance is very troublesome and cannot be taken care of by a press of this type.

The other type, which is hand closed, is far more effective so far as enabling the operator to dispose of the difficult lays, but it possesses another disadvantage in that it requires the attention of the operator until the press is closed before final pressure is applied.

Summing up the foregoing disadvantages the obvious conclusion is that an ideal press would be one which would close automatically after being tripped off and apply and hold

the final pressure until released with the closing feature arranged in a manner such that on the difficult lays the operator could feel that the press could not harm her and that she could interrupt and manually hold back the closing to the extent of allowing the head to grasp the material as she had arranged it and as she retired her hand from it with power coming on automatically thereafter to complete the pressing operation. A press of this type would possess the desirable speed for the major portion of the operations which could be automatic and at the same time would lend itself to the manual manipulation necessary to meet the demands of the operator in handling the smaller in number, but yet important lays which cause the trouble and loss of time.

The present invention therefore contemplates a press of the wide opening head and bed type with power means for exerting final pressure and with a head and support therefor arranged in a manner such that when the press is open the head is latched in such position against a normal tendency to close by gravity. A controlling mechanism is provided for the press and is arranged in a manner such that when the head and its support are released to close by gravity, the pressure releasing circuit is open and when the head engages the work, or is in a safe position, another controller or switch is closed, initiating the power operation which results in power being applied to the press and held until the controller has been again actuated, which operation closes the pressure releasing circuit previously opened thereby producing the opening of the press. The operation of creating the final pressure upon the work also serves to latch the head support to the power mechanism so that when the press opens, the head, being latched to this mechanism, remains open until released.

To improve the facilities for performing the difficult lays, the head may be swivelled to its support and weighted or otherwise counter-balanced by a spring so that it is out of perfect matching or nesting relation with respect to the bed, or in other words, so that its

55

60

65

70

75

80

90

95

100

front edge will contact with the bed or work before the rear portion reaches the ironing surface. This arrangement assists the operator in the difficult lays in the fact that the material would be grasped before the head had settled upon the bed and produced the power operation, thus expediting the difficult lays and also preventing injury to the operator.

10 Other features of the invention will be brought out in connection with the following description, drawings and claims.

Referring to the drawings, Fig. 1 is a side elevation of the machine shown in open position with parts in section; Fig. 2 is a side elevation showing the head nearly closed before the power mechanism is set in operation, with parts in section; Fig. 3 is a section on the line 3—3 of Fig. 1; Fig. 4 is a sectional view of the release controller; Fig. 5 is a section upon the line 5—5 of Fig. 4; Fig. 6 is a sectional view partly in elevation of the power pressure controller; Fig. 7 is a section upon the line 7—7 of Fig. 6; Fig. 8 is a view partly in section showing the commutator or timer; Fig. 9 is a view partly in elevation and partly in section showing the timer in another position; Fig. 10 (Sheet 2) is a schematic wiring diagram; and Fig. 11 shows the press provided with a guard.

In the drawings, 1 represents a standard or frame provided with a rearwardly and upwardly extending hand lever supporting arm 2 adapted to receive the head lever pivot shaft 3. Pivoted upon this shaft is the head lever comprising the rear arm 4 provided with a tail 5 for receiving the counter balancing weight 6 adjustably held upon said tail by a set screw 7 and a forwardly extending arm 8 provided with a head pivot shaft 9 of triangular cross section, as shown. This forward portion 8 is usually in two spaced parts common to this type of machine and each side portion is extended out to receive a handle 10.

45 Beyond the pivot 9 the side portions 8 are connected by a cross piece 11 provided with a spring adjusting screw 12. Pivoted loosely upon the head pivot shaft 9 by means of ears 13 is the heated head 14. This head is pro-

50 vided with an upwardly extending stop 15 engaging a corresponding stop 16 arranged upon the forward portion 8 of the head lever. These stops are normally held in engagement by a spring 17 arranged between screw 12

55 and a suitable centering device 18 on the head forward of the ears 13. The arrangement of the stops 15 and 16 and the spring 17 is such that the head is tilted slightly out of its proper matching or nesting relation with respect to the bed to be described, as shown in Fig. 2. In other words, the front edge of the head is tilted down so that it will engage the front edge of the bed, as will appear.

Rising upwardly from the frame or stand-

ard 1 is a bed or buck support 19 provided

with the usual padded bed 20 which is of area and shape corresponding to the head 14. It is good practice to have the meeting face of the head and bed in substantially a horizontal plane with the pivot 3 and when the head is tilted so that its front edge meets the bed first, as shown in Fig. 2, the further meeting of the two pressing members will be accomplished without any considerable sliding of one upon the other.

70 I prefer to have the weight of the forward portion of the head and its lever greater than the rear portion and its counter balanced weight 6 so that there is a tendency for the head to gravitate toward the work upon the bed, and in order to regulate the speed of travel of the head toward the bed I utilize any suitable retarding device such as a governor, which may be in the form of a cylinder

75 and piston structure comprising a cylinder 21 provided with an ear 22 secured to a pin 23 in an ear 24 forming a part of the frame member 2. This cylinder is provided upon one side with a hollow channel member 25 communicating at 26 with the top of the cylinder and the bottom at 27.

80 At the opening 26 a suitable bleed valve 28 is provided and this valve is adapted to regulate the flow of fluid from the top to the bottom of the cylinder. Slidably mounted within the cylinder 21 is a piston 29 provided with suitable ports 30 through it.

85 This piston is rigidly secured to the lower end of the piston rod 31 which passes through a suitable stuffing box 32 at the top and is connected to a clevis 33 pivoted to a pin 34

90 mounted in an ear 35 forming a part of the rear portion 4 of the head lever. Slidably mounted upon the piston rod with limited movement above the piston is an annular valve 36 adapted to lap and close the ports 30 when the piston moves upward, or, in other words, when the head and head lever move toward pressing position. This cylinder and piston structure thereafter serves as a governor to control the downward movement of the head and the speed of closing may be obviously varied at will by the manipulation of the valve 28.

95 It is obvious from the foregoing description that with the mechanism as already de-

100 scribed the head would have a normal tendency to move toward the bed, and, with the front edge of the head tilted, such edge would engage the ironing surface of the bed in advance of the remaining portion of the ironing face of the head, but continued settling of the head takes place until the head and bed meet in matched ironing relation. It is also obvious that the head does not have a tendency to open and that some means must be employed to open it.

105 The power means for exerting final pressure and for opening the head comprises motor means in the form of an electric motor 37 mounted upon a suitable bracket 38 secured

70

to the frame and having its shaft 39 entering a reducing gear casing 40, where it is provided with a worm 41 meshing with a worm wheel 42 mounted upon the main crank shaft 43 extending through the frame and provided with a crank 44 within the frame. This shaft also extends out beyond the opposite side of the frame where it is provided with a timing device to be described. Connected to the crank 44 is a connecting rod 45 pivoted to a pin 46 arranged in a double toggle link comprising the links 47 pivoted at 48 to the frame and arranged on the outside of an upper toggle clevis consisting of a shank 49 and side arms 50 arranged on each side of the end of the connecting rod 45. The shank 49 of the upper toggle clevis is bored to receive loosely the lower end of the upper toggle rod 51 which is threaded on its lower end to receive a stop nut 52. Surrounding this rod above the shank 49 is a tension spring 53 surrounding the rod and forced against the shank 49 by adjusting nut 53^a threaded on the rod. The upper toggle rod is still further provided with an elongated collar 54 provided with an enlarged head 55 for a purpose to be described. The rod is extended upwardly through a swivel block 56 provided with trunnions 57 entering suitable openings in the side arms of the rear portion 4 of the head lever. This block 56 is provided with rearwardly extending ears 58 receiving a pin 59 upon which is mounted a latch 60 having a latching hook 70 adapted for engagement under the enlargement 55 when the power mechanism is in "off" position, shown in Fig. 1, and the head is up. The block 56 slides freely upon the rod so that the head may move down when the latch is released, but when power pressure is applied to the work the collar 54 engages the block 56 and the latch becomes engaged. When the power mechanism returns to "off" position the head is carried upward through the instrumentality of the latch and remains in this position until the latch is disengaged. The latch is caused to automatically engage the enlargement or head 55 by reason of a spring 71 engaging a tail portion 72 forming a part of the latch and extending above the latch pivot 59.

The latch 60 is released by a controller rod 73 mounted in suitable bearings 74 in the buck support 19. This rod also has bearings 75 in a release switch casing 76 which is secured to the side of the arm 2 of the frame by cap screws 77.

The rod extends beyond the casing 76 at the rear to a point where it is free to engage a lug 78 extending laterally from the latch 60 so that when the rod is pushed back the latch is engaged and released, thus releasing the head. In performing this release operation, however, the rod must throw the release switch into the "off" position and this is ac-

complished by means of a spring 79 anchored in the rod within the casing 76 and engaging a pin 80 on a switch frame 81 supported on suitable pivots 82 mounted in the sides of the casing 76. This switch frame is insulated from and carries a conductor bridge 83 adapted to close the circuit between two contacts 84 and 85 which are in the release circuit of the power means, as will appear. It is obvious that when the rod 73 is moved to the rear of the machine, as shown in Figs. 1 and 4, the spring 79 will pass the pivot point of the switch frame and cause the bridge member to be withdrawn from engagement with the contacts thereby breaking the circuit. The switch frame is limited in its open position by a cross bar 86. When the rod 73 is pulled forward to the position shown in Fig. 4, the spring 79 against passes the pivotal point of this lever and causes the switch to close, closing the circuit to the power means and producing the release operation.

In order to close the circuit to the motor for the pressure producing operation, the machine is provided with a plunger switch shown in Figs. 6 and 7 and comprising a casing 87 secured to the frame of the machine and provided with a switch chamber 88 separated from the frame and spring chamber 89 by a diaphragm or wall 90. The casing is also provided with a lower bearing 91 and a cap 92 carrying an insulating block 93 supporting two contacts 94 and 95 in the pressure applying part of the circuit of the motor means. These contacts are adapted to be engaged by a contact member or bridge 96 insulated from and mounted upon a rod 97 supported in the bearing 91 and also in a bearing in the insulating block 93. A spring 98 surrounds this rod in the spring chamber 89 and bears against a collar 99 secured to the rod and against the underside of the partition 90 and serves to hold the switch open, as shown in Fig. 6. The rod where it extends beyond the cap 92 is provided with an elongated clevis 100 carrying a pin 101 passing through a slot 102 in a link 103 pivoted at 104 to one of the side arms of the rear portion 4 of the head lever, as shown in Fig. 1. The casing 87 is secured to the frame by means of a bracket 105 provided with bolt openings 106 to receive bolts 107 passing into the frame. As the head is finally seated upon the bed and preferably after its front edge has engaged the bed, the pin 101 raises the contact bridge member 96 sufficiently to enter between the contacts 94 and 95 and the power producing circuit is completed.

To stop the motor means at the end of the pressure producing operation and at the end of the opening operation, the machine is provided with a suitable timing switch connected in the electrical circuit and this timer will now be described. As illustrated, it comprises

79

75

80

85

90

95

100

105

110

115

120

125

130

a suitable casing 109 provided with a radially and outwardly extending ear 110 having a circumferentially extending slot 111 through which a bolt 112 is screwed into the machine frame. The elongated slot 111 permits slight adjustment of the casing 109 around the axis of the shaft 43 at the center of said casing, the purpose of said adjustment being readily apparent. Casing 109 carries insulating blocks 113, 114 upon which are the upper and lower segments 115 and 116, the ends of said segments being separated by gaps 117. The timing switch casing surrounds the crank shaft 43 which extends across the frame, and said shaft within the switch casing carries an insulating block 118 provided with a continuous conducting ring 119 to which is electrically connected a swinging contact arm 120 whose shoe end is pressed outwardly against the segments 115 and 116 by a suitable spring 121. A third insulating block 122 is also provided with a post 123 carrying a similar contact arm 124 pressed against the ring 119 and electrically connected with the post 123 to which one of the line wires is connected. Both of the insulating blocks 113, 114 are adjustable rotatably in the casing 109, for a purpose which will later appear. Specifically, each of said insulating blocks on its outer face bears against and rests upon a pair of bosses 126 extending inwardly from the casing wall, said bosses having circumferentially extending slots 127 through which extend clamping bolts 128 for clamping the insulating blocks to the casing. The circumferentially extending slots enable the clamping bolts to be loosened up and the insulating blocks with the conducting segments carried thereby to be adjusted circumferentially of the casing.

Referring to Fig. 9 shaft 43 rotates in the clockwise direction, the arm 120 wiping in turn over each segment. The far end of each segment is curved inwardly, as at 129, so that as the shoe passes beyond the end of each contact it is lifted away from its normal path of movement and suddenly jumps off from one segment, producing a quick break, and then suddenly engages into ample electrical contact with the next segment.

The electrical control and the wiring diagram is set forth in Fig. 10, wherein the motor 37 is connected to incoming line wire L¹ with its other lead 130 branching into two lines, one of which 131 leads to the contact 84 and the other of which 132 leads to the contact 94 of the head closing plunger switch. The other contact 95 of this plunger switch is connected by a wire 133 to the upper contact segment 115 of the timing switch. The movable contact shoe 120 of this timing switch, which is operated by the crank shaft 43, is electrically connected to the other line wire L². The other contact 85 of the control rod switch or power pressure switch is connected by a wire

134 with the lower segment 116 of the timing switch.

When the press is open and ready for use, the parts are in the position shown in Fig. 1, with the head latched up by the latch 60. When the operator has placed a garment upon the bed the control rod 73 is shifted rearwardly carrying the spring 79 of the releasing switch from the position shown in Fig. 4 to that shown in Fig. 2 and also engaging the lug 78 of the latch releasing it from the power mechanism with which it is in engagement and allowing the head to settle by gravity toward the bed, the fluid cylinder and piston governor producing the desired speed of closing. As the head approaches the bed the tilted front edge engages the work and holds it thus relieving the hands of the operator for the remainder of the closing operation, which is preferably the period required for the actuation of the plunger power pressure producing switch in the casing 87 shown in Fig. 6. The closing has produced the upward movement of this switch by reason of the pin 101 being engaged by the end of the slot 102. When this switch is closed the circuit is closed through the upper half of the timing device and the motor applies pressure by moving the crank arm 44 and link 45 into the rear straight line position from that shown in Fig. 1. This straightening of these members straightens the main toggles at the rear of the press and causes the collar 54 to engage the swivel block 56 and produce heavy final pressure. In the meantime the shoe 120 has moved off of the segment 115 and thus broken this circuit when the press will stand at rest with pressure upon the work. The production of final pressure has in the meantime produced the locking of the head lever to the power mechanism by reason of the latch 60 having engaged underneath the enlargement 55. When the operator wishes to release the press from final pressure, the rod 73 is pulled forward causing the spring 79 to be moved toward the position shown in Fig. 4, when the switch lever 81 will be moved between the contacts 84 and 85 and the opening circuit will be established through the wire or lead 134 and through the lower contact segment of the timer which is at that time being engaged by the shoe 120 connected to the line wire L². It is obvious that as the head moves upward the plunger power producing switch in the casing 87 moves to the open position, thus breaking the power producing circuit. When the press is fully open the shoe 120 of the timer moves off of the contact segment 116 around to the segment 115, thus breaking the opening circuit and causing the motor means to come to rest. The latch 60 remains latched and therefore holds the head in open position against the tendency of its over-balancing to close it. The parts remain in this position until the press is ready for another operation.

Let us assume that seventy-five per cent of the pressing operations are automatic, that is, the garment is laid upon the bed and pressed without any special attention from the operator. In other words, let us assume that these automatic operations require no special lay except the straightening of the garment upon the bed. Throughout all these operations it is only necessary for the operator to press the control rod 73 to the rear after which the press will close, exert final pressure and come to rest and remain in that condition until released. For the other twenty-five per cent of the operations special attention is required by the operator and by this it is meant that the operator must hold some of the parts in the desired position or lay until they are engaged by the head. For this type of operation the machine is especially adaptable because, with the tilted head, the front edge of the buck moves down, clamps the work in place and permits the withdrawal of the hands of the operator before the press head moves into the power applying zone. After the work is clamped the operator may then attend to the other matters as no further attention is required to produce the final pressure. If the lay is particularly difficult the operator may even grasp the handle on the head as it is moving down and seat is upon the work as desired without any danger of the power mechanism being brought into action. Indeed, the operator may even raise the head by hand to correct or change the lay and thereafter permit it to again settle upon the work to meet any desired type of manipulation.

From the foregoing, it will be seen that the press disclosed in this application is one wherein the head is released at the will of the operator to close automatically without danger and subject to the will of the operator with an ultimate automatic production of power pressure upon the work, the press opening to full open position upon pressure release.

When a guard is used with the press the forward portions 8 of the head lever are provided with downwardly extending brackets 135 extending downwardly at the rear of the head, as shown in Fig. 11. To the lower ends of these brackets are pivoted side arms 136 of a guard 137 skirting the head and conforming to the shape and extending around the sides or ends of the head. The side arms extend between pairs of pins 138 and 139 on the ends of the head. The guard is also provided with a handle 140 which may be grasped at any time to arrest the movement of the head. The parts are so arranged that the lower edge of the guard is in horizontal alignment with the lower front edge of the head when the head is tilted and before it is moved into matched or nesting relation with respect to the bed, but when the front edge of the head engages the bed the pins 138 and 139

cause the guard to be moved down past the meeting edges of the head and bed and produce a guarding action.

When a guard is used in this way it will be seen that it does not extend down below the entrance to the press when the head is closing or, in fact, until the front edge of the head engages the bed and starts to settle into matched pressing relation. This is extremely important because it permits the operator to manipulate the head and the lay until the work is grasped by the press, after which the guard moves down and serves to remove the hands of the operator from the pressing members. If the operator should leave her hand between the pressing members, the guard itself would prevent the tilting and settling of the head to the extent of operating the power means thereby avoiding danger to the operator's hand as well as avoiding the production of an imperfect pressing operation. The operator may grasp the handle 140 at any time and either raise the head freely or let it settle upon the work at any desired speed.

Having described my invention, I claim:

1. A pressing machine, comprising a substantially stationary pressing member, a pressing member movable into and out of pressing engagement therewith, means causing the front edge portions of said members to engage prior to the full matched engagement of said members, power operated means for producing final pressure between said members, and means effective only after the engagement of the front edge portions of said pressing members for actuating said power operated means to apply final pressure between said members.

2. A pressing machine, comprising a substantially stationary pressing member, a pressing member, movable into and out of pressing engagement therewith, means causing the front edge portions of said pressing members to engage prior to the full matched engagement of said members, power operated means for applying final pressure between said members, means for actuating said power operated means to effect the application of final pressure between the pressing members, and a part movable with the movable pressing member for operating said actuating means, said part being effective to operate said actuating means only after the engagement of the front edge portions of said pressing members.

3. A pressing machine, comprising a substantially stationary pressing member, a movable pressing member normally tending to move into pressing engagement therewith to thereby close the press, power operated means for moving said movable pressing member out of engagement with said stationary member to thereby open the press, a single means for maintaining said press in open condition,

and means for controlling said power operated means and said maintaining means.

4. A pressing machine, comprising a substantially stationary pressing member, a movable pressing member normally tending to move into pressing engagement therewith to thereby close the press, power operated means for applying final pressure between said pressing members and for moving the movable pressing member out of engagement with said stationary pressing member to thereby open the press, latch means for maintaining the press in open condition and movable with the movable pressing member, and a single means for controlling said power operated means and said latch means.

5. A pressing machine, comprising a relatively stationary pressing member, a pressing member movable into and out of pressing engagement with said stationary pressing member, means causing the front edge portions of said members to engage prior to the full matched engagement of said members, means for operating said movable pressing members, means for moving said movable pressing member, a guard normally unobstructing the entrance to the space between said pressing members, and means for moving said guard across said entrance as the pressing members move into full matched engagement.

6. A pressing machine, comprising a substantially stationary pressing member, a pressing member movable into and out of pressing engagement with said stationary member, means causing the front edge portions of said members to engage prior to the full matched engagement of said members, means for moving said movable pressing member, a guard movable with said movable pressing member, means for holding said guard from moving across the entrance to the space between said pressing members when said members are separated, and connecting means between said guard and the rear portion of the movable pressing members, whereby movement of the movable pressing member into full matched engagement with the stationary pressing member effects movement of the guard across the entrance to the space between said pressing members.

7. A pressing machine, comprising a substantially stationary pressing member, a pressing member movable into and out of pressing engagement with said stationary pressing member, means causing the front edge portions of said pressing members to engage prior to the full matched engagement of said members, power operated means for effecting final pressure between said members, control means for actuating said power operated means to effect the application of such final pressure, connecting means between said movable pressing member and said control means and including a lost motion device

which effects a delay in the actuation of said power operated means to effect the application of final pressure between the pressing members until after the engagement of the front edge portions of said pressing members, a guard adapted for movement across the entrance to the space between said pressing members, and an operative connection between said guard and the movable pressing member, whereby an obstruction to the movement of said guard prevents the matched engagement of said pressing members and thereby prevents the actuation of the power operated means to effect the application of the final pressure between the pressing members.

8. A pressing machine, comprising a frame, a bed, a pressing head support mounted for movement upon said frame, a pressing head carried by said support and bodily movable therewith, said head and said support being so constructed and arranged that they have a natural tendency to move so as to cause said head to engage said bed, said head being mounted upon said support for tilting movement with respect thereto so that said head can be tilted into matched engagement with the bed, means for holding said head separated from said bed, power means operatively connected with said support for effecting the application of final pressure between said head and said bed and for effecting movement of said head and said support so as to bring about separation of said head and said bed, and a controller for said power means having operative connections with a part movable with said head, said connections including means whereby said power means is only effective to effect the application of final pressure between the head and the bed after said head has been tilted into matched relation with said bed.

9. A pressing machine, comprising a substantially stationary pressing member, a movable pressing member normally tending to move into pressing engagement therewith to thereby close the press, power means effectively disconnected from the movable pressing member when the press is open so that said power means is incapable of closing the press, means for operatively connecting said power means to the movable pressing member to effect the production of final pressure between the pressing members, means for operatively connecting said power means to the movable pressing member for effecting opening of the press, means for holding the press open, and a controller for said power means, said controller being movable for contact with and for actuation of the means for holding the press open, whereby the movable pressing member may be released for engagement with the stationary pressing member.

In testimony whereof I hereby affix my signature.

BLUFORD W. BROCKETT. 130

CERTIFICATE OF CORRECTION.

Patent No. 1,744,441.

Granted January 21, 1930, to

BLUFORD W. BROCKETT.

It is hereby certified that error appears in the printed specification of the above numbered patent requiring correction as follows: Page 2, line 33, for the word "hand" read "head"; page 3, line 84, for "against" read "again"; page 5, line 30, for "is" second occurrence read "it"; same page, line 129, claim 3, strike out the word "single" and insert the same before the word "means" in line 1, page 6, same claim; and that the said Letters Patent should be read with these corrections therein that the same may conform to the record of the case in the Patent Office.

Signed and sealed this 13th day of May, A. D. 1930.

(Seal)

**M. J. Moore,
Acting Commissioner of Patents.**
